UNITED STATES PATENT OFFICE.

THORVALD N. GARSON, OF NEW YORK, N. Y.

CRANE.

1,337,400.

Specification of Letters Patent. Patented Apr. 20, 1920.

Application filed September 20, 1918. Serial No. 254,892.

To all whom it may concern:

Be it known that I, THORVALD N. GARSON, a citizen of the United States, residing in New York city, in the county and State 5 of New York, have invented certain new and useful Improvements in Cranes, of which the following is a specification.

This invention relates particularly to that class of crane which forms the subject of 10 my Patent No. 1,228,659 of June 5, 1917, its characteristic being the provision of a single hoisting rope for the load and boom, two interengaging members being located at the base of the boom for automatically locking 15 the latter in any elevated position to permit the lowering of the hoisting rope. The object of the present improvement is to provide a heavy-duty crane of this class, for instance a locomotive or heavy truck crane 20 capable of handling a load of five tons or more. The characteristic of the present improvement is the combination of the mast, boom and interengaging boom-locking members in such relationship that the boom 25 in its reaction upon the said locking members is a lever of the second class only, and thus the strain upon the locking members is reduced to a minimum. Furthermore, when the said interengaging locking mem- 30 bers consist of a ratchet and pawl, as in the embodiment of the invention hereinafter described, the size (and hence strength) of the ratchet teeth and pawl may be largely increased over the corresponding parts when 35 acted upon by the boom as a lever of the first class.

The invention will be understood by reference to the accompanying drawing, in which:

40 Figure 1 is a side elevation of a truck crane embodying the invention; and

Fig. 2 is a plan view of the crane.

In the present embodiment of the invention the crane is mounted upon an electric 45 truck A, the supporting frame B for the crane being disposed at the rear end of the truck. As in the construction described in my aforesaid patent, the mast comprises a central stationary shaft C, which in this 50 instance is tubular, and the rotary vertical channelled plates 1 which are secured near their upper ends to a bearing 2 surrounding the shaft. The plates 1 also are secured to a lower bearing member 3, intermediate 55 which and a bearing block 4 may be dis-

posed a series of rollers or ball bearings (not shown).

The boom comprises two channelled bars 5 pivotally mounted at 6 upon a bracket plate 7 carried by and rotated with the 60 plates 1, the bars 5 straddling said bracket plate. The supporting frame B provides a housing for the hoisting drum 8 which is driven from a battery D by means of motor 9 through the instrumentality of suitable 65 gears. The hoisting rope 10 leads upward through the tubular shaft C and thence over a guide wheel 11 to a sheave 12 at the end of the boom, the rope then being looped about the pulley of a block 13, and its end 70 being secured at 14 to the boom. It will be seen that the winding in of the hoisting rope will raise the load until the contact 13* of block 13 meets wear plate 15 at the end of the boom. The boom then will be raised, 75 so that the load will be swung back toward the mast, the boom finally reaching the position shown in dotted lines E, Fig. 1. In order that the load may be lowered upon the truck at the point over which it is swung 80 by the boom, means are provided for automatically locking the boom in its elevated position to permit a reverse movement of the hoisting rope. The said means will now be described.

85 It will be seen from the accompanying drawing that the bracket 7 is provided with a segment rack 7* which is located intermediate the pivotal point 6 of the boom and the free end of the latter. The said rack 90 is engaged by a pawl 16 carried by a shaft 17 which, in this instance is journaled in bearing bosses 18 depending from the bars 5 comprising the boom. To shaft 17 is fixed a lever arm 19 connected by a cable 20 with 95 slide bar 21 having a handle 21* by means of which the pawl may be moved out of engagement with the ratchet against the tension of a spring 22. It will be understood that, if desired, the ratchet-segment may be 100 placed on the boom and the pawl on the bracket 7, and that any other suitable interengaging locking members may be substituted for the ratchet and pawl construction just described.

105 Slightly in advance of the pivotal connection of the boom with the bracket 7 the latter is provided with a bearing roller 23 which is adapted to run upon the annular bearing block 4 as a trackway and thus 110

serves to relieve both the mast and the lower or thrust bearing of strains. It will be noted that the crane is so mounted as to be capable of a complete revolution about 5 the bearing shaft C. This is of great advantage when the crane is installed upon a truck in that it can be swung into position to load or unload a "trailer." In the present instance the crane is revolved by 10 hand, a lever handle 24 being secured to the bracket 7 for the purpose. It will be understood, however, that whenever desired the crane may be revolved by suitable operative connections with the source of power. 15 It will be seen that for a given vertical movement of the boom the locking members 16, 7* have a greater relative movement comparatively with similar locking members when disposed intermediate the pivotal 20 point 6 and the mast. Thus when the locking members consist of a segment rack and pawl, the teeth of the rack may be made of substantial size and depth, and likewise the pawl may be made of a size to resist 25 great strain. And inasmuch as in the present construction the boom when carrying the load acts upon the locking members

as a lever of the second class only, the capacity of the crane is very largely increased, as will be understood without further explanation. 30

What I claim is:

In a crane, the combination with a support, of a hoisting drum and driving means therefor, a boom pivotally mounted upon 35 the support, a hoisting rope connected with the drum and led over the end of the boom, means including the hoisting rope for raising the boom, and two interengaging members, one carried by said support and one 40 carried by the boom, and disposed intermediate the pivotal connection of the boom and the free end of the latter, for automatically locking the boom in its elevated position, whereby the boom will react upon the said 45 interengaging members as a lever of the second class.

Signed at New York, county and State of New York, this 7th day of September, 1918.

THORVALD N. GARSON.
